TEMPLE THREAD CUTTER

Fredric E. Douglas, Hopedale, Mass., assignor to
 Draper Corporation, Hopedale, Mass., a corporation of Maine

Application January 18, 1933, Serial No. 652,345

14 Claims. (Cl. 139—266)

The present invention relates to thread cutting temples for looms.

The usual filling replenishing loom, whether of the bobbin changing or shuttle changing type, requires a thread cutting mechanism to be mounted close to the selvage, to trim off the ends of filling that would otherwise be left hanging from the cloth as an incident to the replenishing operation. Such thread cutting mechanism is usually mounted in the temple on the replenishing side of the loom. Generally speaking, the temple thread cutting mechanism operates continuously, regardless of whether or not there are threads in position to be cut, although some such mechanisms are designed to take into consideration the fact that there are no threads to be cut except immediately after filling replenishment, and accordingly they only operate a few times immediately after each replenishing operation.

It is an object of my invention to provide an improved form of temple thread cutting mechanism.

A further object is to provide an improved timing device for rendering the thread cutting mechanism inoperative after a predetermined number of operations.

Further objects will, in part, be hereinafter more specifically enumerated or will become obvious as the description proceeds.

The preferred embodiment of my invention is illustrated on the accompanying drawings, in which:

Fig. 1 is a side elevation of the head of a temple embodying my invention;

Fig. 2 is a cross-section, taken substantially on line 2—2 of Fig. 1 but with the thread cutting blades and certain other parts not shown in section.

Fig. 3 is a view similar to Fig. 1 but with certain parts omitted or shown in dotted outline, and other parts in different operative relation, as suggested by line 3—3, Fig. 2; and

Fig. 4 is a similar view, except that parts below line 4—4, Fig. 2 are omitted and the remaining parts occupy still a different operative relation.

The temple 1, which includes the usual temple head 2, may be mounted on the loom in any conventional manner, not requiring further mention.

The thread cutting mechanism is, as above intimated, mounted in the temple head, and preferably is comprised of a stationary ledger blade 3 and a movable cutter blade 4 positioned side by side in a guide way 5 extending from front to rear through the temple head.

The ledger blade 3 may conveniently be of the

form shown in my co-pending application S. N. 625,763, filed July 29, 1932. The movable cutter blade 4 consists simply of a flat piece of metal, cast or otherwise formed, and having at its rearward end a depending cutting tip 6, the sharpened cutting edge of which cooperates with a vertical edge 7 formed on the ledger blade.

The guideway 5 is sufficiently narrow to confine the movable cutter blade 4 to movements in a vertical plane. The blade 4 is adapted to both rock and slide in the guideway, but the forward end of the blade is confined against vertical movement while the rearward end is free to move vertically as well as horizontally. Accordingly, the forward end of the guideway is restricted in height, as by two pins 8 formed on or secured to the temple head.

For operating the movable cutter blade, I provide an oscillating member constituted by a short stud 9 bearing directly in the temple head. The stud may be provided with an eccentric portion, as pin 10, engaging in a hole in the cutter blade 4, for operating the latter. Since the stud 9 is transverse to the plane of movement of the movable cutter blade, and eccentric pin 10 engages this blade intermediate its ends, oscillation of the stud will serve to rock and slide the cutter blade. When the cutting tip is up and projected rearwardly, as in Fig. 1, the pin 10 occupies a position horizontally rearwardly of the axis of the stud 9. From this position the stud oscillates clockwise, till the pin is down (see Fig. 3). Movement of the stud through approximately 90 degrees will serve to lower the rearward end of the cutting blade, thus hooking the cutting tip behind the filling, and move the blade 4 forwardly to cut the filling thread. Conveniently, the blade 4 is returned to normal position by rotating the stud in the other direction.

The stud 9 is oscillated, preferably by means including an arm 11 fixed thereto. In the present instance, the stud 9 is provided with an enlarged portion 12 and a reduced portion 13, for a purpose subsequently to be described. The extreme end of the stud is still further reduced, at 14, and the arm 11 is provided with an opening fitting over this end 14, the arm bearing flat against the end of portion 13. A pin 15 in the arm engages a hole 16 in the end of portion 13, thus constraining the arm and stud to move together. A screw 17, having an enlarged head, is threaded into the end of the stud the head holding the arm 11 in place.

The arm 11 is moved in one direction, i. e., clockwise in Fig. 1, by being struck by the lay or

a bunter thereon (not shown). A spring 18 is provided for moving the arm in the other direction. The spring has one end looped to engage a pin 19 in arm 11 and, after making several 5 complete turns about the stud, has its other end engaged about a pin 20 in the face of cover plate 21.

The cover plate 21 is held in place by screws 22 passing therethrough and threaded into the 10 temple head. An opening is provided in the cover plate, of sufficient size to admit portion 13 of the stud but too small to permit passage therethrough of the enlarged portion 12, and by this 15 means, the stud and arm are held in place in the temple head.

The thread cutting mechanism thus far described may be used with or without the timing device described presently. In either event, it is susceptible of modification, within the scope 20 of the appended claims. However, the principle involved is particularly desirable in that it will afford a positive control over the path of movement of the cutting tip.

While, as stated, some aspects of my invention 25 do not require the use of a timing device with this type of thread cutting mechanism, the particular form thereof shown is peculiarly susceptible to such use. Accordingly, I have devised, and shown, a simple, efficient timing device for locking arm 11 out of operation after a 30 predetermined number of operations thereof.

In the particular embodiment shown, a ring 23, slightly larger, internally, than enlarged portion 12 of stud 9, is rotatably supported in the 35 temple head in such manner as to be concentric with the stud. The periphery of the ring is provided with a number of small, equally spaced notches 24, and at least one deeper recess 25. The inner periphery of the ring is provided with 40 notches 26 spaced, angularly, the same as the notches 24, although not necessarily aligned therewith. The enlarged portion 12 of the stud is cut out to form a shoulder 27, a wall 28 formed on an arc concentric with the axis of the stud, a pocket 29 and a shoulder 30. A ball or roller 45 31 is positioned within this cut out space. The parts of the timer thus far described constitute a form of one way clutch, whereby oscillation of the stud 9 serves to rotate the ring 23 in one direction only (clockwise, Figs. 1, 3 and 4).

The manner of operation of the one way clutch 50 will be described briefly. Starting with the parts positioned as in Fig. 4, at which time arm 11 is rearward as in Fig. 1, forward movement of the arm a few degrees will rotate stud 9 clockwise 55 without disturbing the ball 31 or ring 23 until shoulder 27 engages the ball. The distance from wall 28 to the bottom of a contiguous notch 26, measured along a radius of the stud, is but a few thousandths of an inch greater than the diameter 60 of the ball, and, in this latter position, the wall keeps the ball in its notch. Continued movement of the arm and stud result in the stud, ball and ring moving together an angular distance corresponding to the spacing between notches 24, where 65 the ring is held by a nose 32 formed on spring pressed latch 33. As the arm and stud move in the other direction (counterclockwise) shoulder 29 rolls the ball out of its present notch 26 into the next one, ring 23 remaining stationary. This 70 operation is then repeated, until recess 25 comes under the nose 32, when the nose drops down into the recess.

The arm 11 is provided with an extension 34 75 which is engaged by the nose 32 when the latter

drops into the recess 25. By this means, the arm, and the thread cutting mechanism, are locked out of operation. The cutting mechanism may be returned to operation at time of filling replenishment, by means of a finger 35 which may be associated with the replenishing mechanism in such a manner as to be raised and held in raised position for one or two picks each time the replenishing operation takes place. Each time finger 35 is raised, and thereby latch 33, the cutting mechanism operates a predetermined number of times and then is again locked out of operation as above described.

It is to be noted that while the timing device herein disclosed is particularly adapted for use with the type of thread cutting mechanism shown, it may, nevertheless, be used with other than this particular cutting mechanism. Also, the timing device itself is susceptible of change, within the scope of the appended claims.

I claim:

1. A thread cutting temple including a temple head having a guideway therein, a ledger blade and cooperating rocking and reciprocating cutter blade mounted in the guideway, an oscillating 100 member mounted in the temple head and having an eccentric portion directly engaging said movable blade for operating the latter, and means including an arm for oscillating said member.

2. A thread cutting temple including a temple 105 head having a guideway therein, a ledger blade, a cutter blade mounted for rocking and reciprocating movements in said guideway, a stud mounted in the temple head transversely of the plane of the said cutter member, said stud having 110 an eccentric portion directly engaging said movable cutter member for operating the latter, and means including an arm for oscillating the stud.

3. A thread cutting temple including a temple 115 head having a guideway therein, a ledger blade, a movable cutter blade mounted in said guideway, the forward end of said cutter blade being confined against vertical movement and the rearward end thereof being movable both vertically and horizontally, the said rearward end of the 120 movable cutter blade being provided with a depending cutting tip, and a member journaled in said head for oscillating movement only, about a fixed axis intermediate the ends of said movable blade and substantially normal thereto, said 125 member engaging said movable blade and imparting to the cutting tip thereof downward and forward movements.

4. A thread cutting temple including a temple 130 head having a guideway therein, a ledger blade, a movable cutter blade mounted in said guideway, the forward end of said cutter blade being confined against vertical movement and the rearward end thereof being movable both vertically and horizontally, the said rearward end of the 135 movable cutter blade being provided with a depending cutting tip, and an oscillating stud mounted in the temple head and having an eccentric portion engaging said movable cutter member intermediate its ends and imparting to 140 the cutting tip thereof downward and forward cutting movements.

5. A thread cutting temple including a temple 145 head having a guideway therein, a ledger blade, a cutter blade mounted for rocking and reciprocating movements in said guideway, a stud oscillatably mounted in the temple head transversely of the plane of the said cutter member, said stud having an eccentric portion directly engaging said movable cutter member for operating the 150

- latter, means including an arm for oscillating said stud, and a timing device for locking the said arm out of operation after a predetermined number of operations thereof.
- 5 6. A thread cutting temple including a temple head having a guideway therein, a ledger blade and cooperating rocking and reciprocating blade mounted in the guideway, an oscillating member mounted in the temple head and having an eccentric portion engaging said movable blade for operating the latter, means including an arm for oscillating said member, and means for locking said arm out of operation after a predetermined number of operations thereof.
- 10 7. A thread cutting temple including a temple head having a guideway therein, a ledger blade, a cutter blade mounted for rocking and sliding movements in said guideway, a stud mounted in the temple head transversely of the plane of the said cutter member, said stud having an eccentric portion directly engaging said movable cutter member for operating the latter, means including an arm for oscillating said stud and means including a one way clutch for locking the said arm out of operation after a predetermined number of operations thereof.
- 15 8. A thread cutting temple including a temple head having a guideway therein, a ledger blade, a movable cutter blade mounted in said guideway, the forward end of said cutter blade being confined against vertical movement and the rearward end thereof being movable both vertical and horizontally, the said rearward end of the movable cutter blade being provided with a, depending cutting tip, an oscillating stud mounted in the temple head and having an eccentric portion engaging said movable cutter, a one way clutch constituted by said stud and a ring and a member transmitting movement of the stud in one direction only to the said ring, means for oscillating said stud, and means controlled by said ring for rendering said first mentioned means inoperative.
- 20 9. A thread cutting temple including a temple head having a thread cutting mechanism mounted therein, which thread cutting mechanism includes a rocking and reciprocating cutter blade, an oscillating stud mounted in said temple head and having an eccentric portion directly engaging and operating said thread cutter blade, and means including an arm for oscillating said stud.
- 25 10. A thread cutting temple including a temple head having a thread cutting mechanism mount-
- ed therein, an oscillating stud mounted in said temple head and having an eccentric portion operating said thread cutting mechanism, means including an arm for oscillating said stud, and a rotary timing device for locking said arm out of operation after a predetermined number of operations, said timing device including a one way clutch operated directly by said arm.
- 30 11. A thread cutting temple including a temple head having a thread cutting mechanism mounted therein, an oscillating stud mounted in said temple head and operating said thread cutting mechanism, means for oscillating said stud, and means operated by the stud for rendering the first named means inoperative after a predetermined number of operations thereof.
- 35 12. A thread cutting temple including a temple head having a thread cutting mechanism mounted therein, an oscillating stud mounted in said temple head and operating said thread cutting mechanism, means for oscillating said stud, a ring surrounding said stud and concentric with respect thereto, a oneway clutch constituted in part by said stud and ring whereby the latter is intermittently rotated in one direction by the former, and means controlled by the ring for rendering said first named means inoperative.
- 40 13. A thread cutting temple including a temple head having a thread cutting mechanism mounted therein, an oscillating stud mounted in said temple head and operating said thread cutting mechanism, means for oscillating said stud, a rotatable ring surrounding said stud, said ring being provided with a recess in the periphery thereof, means whereby oscillation of the said stud rotates said ring in one direction only, and a latch having a nose adapted to enter said recess when said ring is rotated to a predetermined position, said latch rendering said means inoperative when the said nose enters said recess.
- 45 14. A thread cutting temple including a temple head having a thread cutting mechanism mounted therein, an oscillating stud mounted in said temple head and operating said thread cutting mechanism, means including an arm for oscillating said stud, a rotatable ring surrounding said stud and concentric with respect thereto, a ball clutch for rotating said ring from said stud, said ball clutch being constituted by the said ring and stud and a ball positioned therebetween, and a latch controlled by said ring for locking said arm out of operation.
